United States Patent Office

Des. 183,482
Patented Sept. 9, 1958

183,482

BELL RINGING TOY

Silas M. Ford, St. Paul, Minn.

Application June 7, 1957, Serial No. 46,516

Term of patent 3½ years

(Cl. D34—15)

FIG. 1

FIG. 2

FIG. 3

Figure 1 is a perspective view of a bell ringing toy, showing my new design;

Figure 2 is a side elevational view thereof; and

Figure 3 is a front elevational view thereof.

I claim:

The ornamental design for a bell ringing toy, as shown.
